UNITED STATES PATENT OFFICE.

PETER COOPER HEWITT, OF NEW YORK, N. Y., ASSIGNOR, BY MESNE ASSIGNMENTS, TO
COOPER HEWITT ELECTRIC COMPANY, OF HOBOKEN, NEW JERSEY, A CORPORATION
OF NEW JERSEY.

LOW-RESISTANCE VAPOR ELECTRIC DEVICE.

1,156,227.

Specification of Letters Patent.

Patented Oct. 12, 1915.

Application filed August 14, 1907. Serial No. 388,465.

To all whom it may concern:

Be it known that I, PETER COOPER HEWITT, a citizen of the United States, and resident of New York, county of New York, 5 State of New York, have invented certain new and useful Improvements in Low-Resistance Vapor Electric Devices, of which the following is a specification.

My invention relates to means and methods
10 of controlling various reactions at and be-
tween two electrodes separated by a gas or
vapor.

In a gas or vapor apparatus having a negative electrode or cathode, and a positive electrode or anode, or several of either, the normal drop in potential between a positive terminal and a cathode may be, when the cathode or negative electrode resistance is in the low resistance state, somewhere about 15 14 to 20 volts, the cathode being of mercury. I have integrated and analyzed the separate reactions causing the total drop over two electrodes and particularly in controlled and inclosed devices and have determined within 20 25 limits the respective localities and estimated the relative values of their various resistances. The reactions referred to presenting resistance may be most conveniently considered for the purposes of this invention in 30 35 the following subdivisions: 1, those at or around the positive electrode; 2, those in the positive column or gas or vapor path between the positive electrode and the negative dark space; 3, the reactions at the point of transition between the positive column and the negative dark space; and 4, the reactions in the dark space and those at the surface of the negative electrode. The relations or proportions of these four seats

40 relations or proportions of these four seats of sources of potential drop in volts may, for the purposes of this description, be roughly considered as follows: at 1, as 5 to 7; at 2, as 1 to 2; at 3, as 3 to 5; at 4, as 4 to 6. These reactions are modified by 45 gas density and the zone of the reactions is enlarged by increased rarefaction of the gas or vapor, particularly the zone of the reactions at 4. They are affected and varied by gas impurities and other features. As 50 accurate measurements are difficult to obtain separately, due allowance must be made, but the values mentioned serve to give a

fair idea for the purposes of this description. Considering these seats of potential drop, I find that I can modify, if not entirely eliminate, some of the reactions thereby reducing the normal drop in potential between electrodes in devices of this character to a limit considerably lower than has heretofore been used in commercial practice. 60 In certain uses for which vapor devices are serviceable, such, for example, as the well known converters or rectifiers, it is important that the internal heating effect, that is to say, the heat generated by the device 65 in normal operation, should be as small as possible. If, for example, the total drop of potential can be materially modified or reduced, the same device will be able to pass more current for the same amount of 70 heat generated or it will pass an equal current with a considerably smaller development of heat—an important feature in a device where its temperature governs the density. A given device having its normal 75 capacity limited by the ability to radiate heat can be utilized to pass a larger current when the potential drop between the terminals is small than it can when the potential drop over it is comparatively large. 80

I have found that by locating the positive electrode or anode in close proximity to the negative electrode or cathode, so that the reactions at one terminal come under the zone of influence of the other, the total potential drop in the vapor device under similar conditions may be reduced to from 7 to 8 volts and in some cases even lower. My experience has led me to believe that there exists a critical region, limited probably by the dark space adjacent to the negative electrode, within which region the actions at or around the positive electrode, those of the positive column, and those at the joint between the positive column and the dark space, are wholly or partially suppressed, and it is the purpose of this application to render this discovery serviceable in the arts, and it is thought that the disclosure made herein should be a sufficient guide for those wishing to utilize the principles involved in my invention. I have already stated that these reactions are more apparent and more easily controlled when the gas is less dense.

inasmuch as the space in which the control can be accomplished is increased with the rarefaction of the gas. Similarly, the extent or dimensions of the critical region, so far as it is represented by the dark space are increased by an increase of current. It appears further that in order to secure the best results electrodes should be placed within this critical region in such relation to each other as to cause the reactions at one electrode, a negative, to affect those of the other, a positive. Under these conditions, the positive and negative reactions may be said to occupy substantially the same space or be within the same zone of influence. Assuming that the electrodes are suitably located within the dark space, the distance of physical separation between said electrodes may be varied without seriously affecting the results, by varying the quality of perfection of the vacuum in the container within which the electrodes are inclosed. The more perfect the vacuum, the more widely the electrodes may be separated without altering the results. Or, looked at in another way, the current-carrying-capacity of the vapor device, assuming a fixed relation between the electrodes within the critical region, may be increased by a decrease of density therein. This current-carrying-capacity, in its turn, is increased by an increase of current for the same density, since the increase of current may of itself extend the dark space.

While I am not prepared to state the exact cause of the action described herein, as it is probably very complex, and while I am not able to state the exact degree in which the various resistances are modified or reduced, yet from my investigations it appears as if, under the conditions recited, reactions noted above as 1 and 2 are very materially lessened, if not substantially suppressed, while the reactions which take place at 3 appear to be modified to a very great extent.

This discovery is useful in connection with gas or vapor gaps, vapor converters, interrupters, electric valves, and other devices, and may be adopted advantageously in connection with the electrodes for a keep-alive circuit.

The apparatus in which my discovery may be embodied may take various forms and I have only thought it necessary to illustrate a few such forms in the following figures of drawing, which represent three several ways of embodying my discovery in useful types of apparatus, together with a detail in Figure 4 of a modification.

Referring to the drawings, Fig. 1 shows a bulb, 1, having a negative electrode or cathode, 2, of mercury, or other self-reconstructing material, and having two positive electrodes or anodes, 3 and 4, of solid material, such as iron. The circuit wires, 5 and 6, connected with the leads, 7 and 8, of the

respective positive electrodes 3 and 4, pass through reentrant portions, 9 and 10, of the glass bulb and the leads themselves beyond that point are surrounded by glass protecting sleeves, 11 and 12, to points 70 near where they are connected with the main body of the positive electrodes 3 and 4. The anodes themselves are caused to approach the mercury cathode to within a very short distance and be within the zone 75 of influence. Each anode is surrounded by a shield, 13, of glass intended to remain physically unchanged during the operation of the device and thus permitting the anodes to be approached as much as possible to the 80 negative. The positive electrodes 3 and 4 are connected, respectively, to the terminals of a coil, 34, constituting the secondary of a primary, 33, connected with a source of alternating current. The transformer thus 85 indicated is simply chosen for purposes of illustration and any suitable source of alternating current may be substituted to suit different conditions. An intermediate point of the secondary 34 is connected to the negative electrode 2 as shown. These connections are now well known as those of a vapor converter or rectifier and they are simply illustrated for the sake of clearness. With the 90 positive electrodes placed as shown in Fig. 1 95 in close proximity to the negative electrode 2, the resultant converter or rectifier may be operated without excessive heating with comparatively large currents, the drop of potential between the positive and negative 100 electrodes being reduced considerably below what is normal in the case of a wide separation of the said electrodes, or where the electrodes are not subject to mutual influence.

In Fig. 2 I have shown a device which is adapted to be used as an electric valve and particularly adapted for high vibratory currents such, for example, as may be used in wireless transmission. Here the active positive electrode is shown at 14 in the form of a disk of iron or other solid conducting material, while a keep-alive positive electrode, 15, is shown as a ring or disk connected with a lead, 16, surrounded by a sleeve, 17, of glass. The electrode 15 is arranged in very close proximity to and under the influence of the negative electrode 2 and is connected to one terminal of a source, 18, of direct currents, the said source being connected to a lead, 19, running to the negative electrode 2. In the circuit of the source 18 I introduce a variable resistance, 20, and an inductance, 21, which may also be variable, 110 as shown. While the apparatus is in operation, the circuit of the source 18 is kept closed and current always passes through the circuit, any suitable means for starting the flow of current being adopted. By reason of the close proximity of the positive 115

electrode 15 to the negative electrode 2, the resistance of the described circuit inside the vapor device 1 is comparatively small. One lead of a source of variable current is connected to the lead 40, while the other terminal, if one is used, is connected either at 16 or 19. In order to avail of the valve action of the device it is only necessary to connect a direct current translating device in 10 parallel circuit between these two leads having inductance, 24, in its circuit. I have shown the positive electrode 15 as being connected beyond its point of union with the circuit of the source 18 to ground at G. To 15 the ground circuit I have connected a circuit 22 containing a direct current translating device, 23, and an inductance, 24. To the circuit 22 is connected by a conductor 25 the main positive electrode 14. The conductor 20 22 may be continued in the form of an antenna, 26, subject to the influence of vibratory currents such as are used in wireless telegraphy or of any kind of power. The inductance 24 may be omitted provided the 25 inductance of the translating device 23 is sufficient in itself without the additional aid. The translating device 23 may be an ordinary telephone receiver, a direct current motor, or other suitable apparatus adapted to 30 translate the energy received.

In Fig. 3 I show a device somewhat similar to that illustrated in Fig. 2, but more especially adapted for the rectification of simple alternating currents. The positive 35 electrode which in the previous figure was called the main positive electrode is here dispensed with and the electrodes 15 and 2 are connected to the terminals of an alternating current source shown at 27 and 28 as 40 being, respectively, the primary and secondary of a transformer. In this case I show a starting band 29, connected by a conductor, 30, with one side of the circuit to assist in starting operation which starting operation, 45 may, however, be accomplished by any method that may be preferred. In this instance the electrode 15 becomes the main positive electrode of the device and owing to the well known action of apparatus of this 50 kind current will only pass in one direction through the device, the waves of opposite polarity being suppressed by the action of negative electrode resistance at the positive electrode. Accordingly, the circuit, 31, will 55 be traversed by a pulsating current of uniform direction, but not by an alternating current. At 32 is shown a translating device for utilizing the rectified current. In this case also the electrode 15 is placed in 60 very close proximity to the negative electrode 2 and the normal potential drop over the device is thereby greatly reduced.

In the figures of the drawing the lead to the negative electrode is represented as being 65 connected with a piece, 35, of platinum,

iridium, iron, or other suitable conducting material, constituting a point which projects slightly above the surface of the mercury which in the case of currents of small magnitude is useful but is not essential with 70 very large currents.

Referring again to Fig. 1, the circuit between the negative electrode and an intermediate point of the secondary 34 is marked, 75 36, and includes a number of translating devices, 37, and an inductance, 38.

In Fig. 4 I have shown an arrangement of positive electrodes which differs from that illustrated in Fig. 1 and in some cases may be found more desirable. The two positive 80 electrodes 3 and 4 are arranged in this instance, respectively, on the inside and outside of a vessel, 39, of glass or other suitable material, the said vessel being generally cup shaped and having a central re-entrant open boss or cylinder, 41. The electrode 3, for example, is in the form of a ring 85 surrounding the boss and connected through the vessel to the lead wire 5. The electrode 4 stands above the opening in the base of 90 the cup, or, say, at the upper end of the boss, 41, and is connected to the lead 6. With this arrangement both positive electrodes 95 may be brought into sufficiently close proximity to the negative electrode 2, while being amply protected from short-circuiting by the structure shown and described.

I claim as my invention:

1. A vapor electric apparatus comprising an exhausted container, positive and negative electrodes therein, the positive electrode being located and supported within the region in which the negative electrode component of the total fall of potential occurs.

2. A vapor electric apparatus comprising 100 an exhausted container, positive and negative electrodes therein, said container being shaped to offer cooling surface for said apparatus, the positive electrodes being located and supported within the dark space in the 110 neighborhood of the negative electrode.

3. A vapor electric apparatus comprising an exhausted container, positive and negative electrodes therein, the said positive and negative electrodes being separated by less 115 than a critical distance, the limit of which is the dark space adjacent to the negative electrode, whereby the total fall of potential between the terminals of the apparatus is materially less than 14 volts.

4. In a vapor electric device, an exhausted container, a negative electrode therein of volatile self-reconstructing material, and a positive electrode therein of solid material, the said positive electrode being located 125 within a critical region limited by the negative electrode and the region of approximately the same potential adjacent to said negative electrode.

5. In a vapor electric apparatus compris- 130

ing an exhausted container, a cathode with
a dark space adjacent thereto, an anode lo-
cated in said dark space in fixed relation to
said cathode, an anode stem connected to
5 said anode and an insulating covering for
said stem, said covering being integral with
said container.

Signed at New York, in the county of New
York, and State of New York, this 7th day
of August, A. D. 1907.

PETER COOPER HEWITT.
